US0D1086427S

(12) **United States Design Patent** (10) **Patent No.:** **US D1,086,427 S**
(45) **Date of Patent:** **** Jul. 29, 2025**

(54) **AIR DISTRIBUTION BOX**

(71) Applicant: **Dometic Sweden AB**, Solna (SE)

(72) Inventors: **Rickard Hederstierna**, Hägersten (SE);
Samuele Meda, Chichester (GB);
Jarrod Williamson, Olinda (AU);
Jason Svarc, Victoria (AU); **Louis Liu**,
JinWan (CN)

(73) Assignee: **Dometic Sweden AB**, Solna (SE)

(**) Term: **15 Years**

(21) Appl. No.: **29/915,483**

(22) Filed: **Oct. 31, 2023**

Related U.S. Application Data

(60) Continuation of application No. 29/774,535, filed on Mar. 17, 2021, now Pat. No. Des. 1,006,977, which is a division of application No. 29/660,094, filed on Aug. 17, 2018, now Pat. No. Des. 917,036.

(57) **CLAIM**

The ornamental design for an air distribution box as shown and described.

DESCRIPTION

FIG. 1 is a perspective view of an air distribution box showing our new design;

FIG. 2 is a first side view thereof;

FIG. 3 is a second side view thereof;

FIG. 4 is a third side view thereof;

FIG. 5 is a fourth side view thereof; and,

FIG. 6 is a bottom view thereof.

Broken lines illustrate portions of the air distribution box that form no part of the claimed design.

1 Claim, 6 Drawing Sheets
